ATTORNEY.

UNITED STATES PATENT OFFICE.

DANIEL W. DUDDERAR, OF MOUNT AIRY, MARYLAND.

RETORT-COVER CLAMP.

Application filed July 9, 1927. Serial No. 204,474.

This invention relates to improvements in clamp devices for covers of vessels and is particularly directed to a quick-acting clamp for retorts or similar vessels on which the heads or covers must be secured sufficiently to withstand internal pressures in the retorts.

One object of the invention is to provide an improved construction of clamp device for retort-covers which may be quickly operated because it is common to utilize a number of fastening devices on a single retort and considerable time is frequently consumed in attaching or detaching the fastenings.

Another object is to provide a clamp structure which may readily be swung into position and quickly seated over the cover-edge to clamp the cover in place.

20 A further object is to provide an improved clamp device which will hold the cover seated against internal pressure up to a desired pressure but will yield when an excessive pressure is produced and permit a 25 venting that will avoid bursting or damage to the retort structure.

A still further object is to provide an improved form of clamp for retort-covers whose clamping pressure may be varied to 30 suit the work the retort has to do.

With these, and other objects in view, in the accompanying drawing is illustrated the invention, wherein,

Fig. 1 shows the top of a retort with a 35 series of the improved clamp devices arranged about the same and in clamping position.

Fig. 2 illustrates an enlarged sectional elevation showing the clamp and a portion of 40 a retort as viewed on the line 2-2 of Fig. 1.

Fig. 3 shows a front elevation of a portion of the clamp and retort, and

Fig. 4 illustrates a horizontal sectional detail through the clamp device on an enlarged scale, showing the structure as it 45 would appear if viewed on the line 4-4 of Fig. 2.

Referring to the drawing, the numeral 5 designates the vessel, tank or retort having 50 a top edge 6 with a packing element 7 therein and with a cover or top 8 of any preferred construction, but in this instance shown as hinged at 9, so as to swing down on, or up from, the top edge 6 of the vessel.

55 The cover has a series of spaced lugs 10

around its periphery forming a radial slot 11 between each pair of lugs and directly beneath each pair of cover-lugs, when the cover is down on the retort, the wall of the latter carries two angle-lugs 12, between 60 which is pivoted one end 13, of a clamp-bar 14, the pivot-pin being designated 15 in the drawing.

Associated with each clamp-bar 14, is an actuating lever 16 and a block 17.

65 The blocks 17 are preferably of rectangular shape in cross-section, as clearly seen on a large scale in Fig. 4 of the drawing, and each block is provided with a vertical slot 18, extending centrally therethrough and of 70 a size to permit the clamp-bar 14, to pass up therethrough.

The actuating levers 16 have an operating-end 19, and a clamping-end 20 and between 75 said two ends said lever is slotted as at 21, which slot extends all the way from the clamping-end to a point designated 22 near the operating-end so that said levers 16 have two spaced jaws 23 which straddle the block 17.

80 A pivot-pin 24, extends horizontally through the spaced jaws 23 of the actuating lever and also through the block 17, and this pin also extends through a vertical slot 25, which is provided in the clamp-bar 14.

85 It is thus to be understood that the actuating-lever 16, block 17 and slotted clamp-bar 14 are all held together by the cross-pin 24, but that the block and lever may have a vertical or longitudinal movement on the 90 clamp-bar 14 within the limits of the slot 25 which is provided in that bar.

The clamp-bar 14, has a central stem 26 projecting up from the block 17, and this stem has the form of a bolt in that it is circular in cross-section and is externally screw-threaded, as clearly shown in Fig. 2 of the drawing.

95 It will be noted, by reference to Fig. 2 of the drawing, that the stem 26 projects from 100 the bar 14, well down in the slot 18, of the block.

On the stem 26 and directly over the block, I provide a coiled spring 27, whose lower end seats on the top surface of the block and over the upper edge of the longitudinal slot 18 therein, and on top of this coiled spring 27, I provide a second and larger coiled spring 28, but I interpose a washer 29 between the two springs merely to ensure a 105 110

proper seat for the lower end of the larger spring against the upper end of the smaller spring.

A washer 30 is provided on the stem at the outer end of the larger spring 28 and an adjusting nut 31 is screwed onto the stem at the outer side of the washer.

The lower smaller spring 27, has very little movement from a closely compressed condition, when the clamp is locked, as in Fig. 2, to its full open position while the larger upper spring provides the clamping power after the smaller spring has been fully compressed until its coils are brought together and this clamping power is brought into use at the extreme final up-movement of the end 19 of the operating lever, as will presently be explained.

The lower ends of the spaced jaws 23, each carry a roller 32, which rollers are mounted on pins 33 whose centers are slightly forward of the centers of the pins 24, on which the levers are pivoted, consequently at the extreme final up-stroke of the lever, when the clamping spring 28 is applying its force down on the block 17 and the arms 23 through the pin 24, the rollers 32, will just pass forward of the center of the pin 24 and snap the clamp-points 34 of the jaws down close on the top or the lugs 10 of the top and remain in the clamping position because the centers are out of vertical alinement.

The clamp-bars 14 obviously swing into the slots 11 between the lugs 10 as the rollers 32, contact with the top surfaces of the lugs and roll thereon while the lever is being swung up to the clamping position.

By reference to Fig. 2, it will be noted that the lower edge of the block 17 is convex. This enables this lower edge to readily ride over the outer ends of the lugs on either the up or down movement of the bar to or from the lug slots 11.

As the lever-ends 19 are swung down, the clamping-end 34 will swing slightly over the cover as the rollers 32 roll back under the center of pivot-pin 24 and during this movement, the pivot-pin 24 will be lowered, drawing the block down with it sufficiently to relieve the pressure of the springs.

The lower end 16 and the upper end of the bar as well as the block 17 thereon, may all be swung outwardly from the radial openings and then hung pendants at the side of the retort while the cover is removed.

When the cover is restored, a reversal of the operation, to wit: swinging clamping-bar 14 up into the opening on the cover, locating the rollers 32 on the cover edge or the edge of the lugs with the block over above, then the preliminary up movement of the lever-end 19, will lift the block and compress the weaker spring until it closes, and at this time, the centers of pins 24 and 33 will be practically in line. Then the farther

up movement of the lever-end will compress the stronger spring and this spring pressure will thus be transferred to the block and the clamping edge 34 of the jaws 23 will snap down on the cover as the center of roller pin 32, passes beyond the center of pin 24.

Having described my invention, I claim,—

1. The combination with a retort vessel, of a cover having radial openings around its periphery, a bar pivotally attached to the vessel below the cover and movable into the radial opening above its pivot-point, a clamping lever pivoted with respect to the bar above the radial opening, spring-means on the upper end of the bar and means operating between the spring-means and the clamping lever to press the latter on the cover.

2. The combination with a retort vessel, of a cover having radial openings around its periphery, a bar pivotally attached to the vessel below the cover and movable into the radial opening above its pivot-point, a clamping-lever pivoted with respect to the bar above the radial opening, spring-means on the upper end of the bar, and a block through which the bar extends said block being engaged by the pivot of the clamping-lever and upon which the spring-means seats whereby to press the block down and seat the clamping lever on the cover.

3. The combination with a retort vessel, of a cover for said vessel said cover having radial openings around its periphery, bars pivotally attached with respect to the vessel below the cover and movable up into the said peripheral openings of the cover, lever means for seating on the cover below the upper end of the bar, roller means carried on said lever means so as to engage the top of the cover and spring-means for drawing the bar up and pressing the lever-means down on the cover to seat the latter on the vessel.

4. The combination with a retort vessel, of a cover for said vessel said cover having radial openings around its periphery, bars pivotally attached with respect to the vessel below the cover and movable up into the said peripheral openings of the cover, a block on the bar and movable longitudinally thereon, lever means having spaced clamping-jaws which straddle the block, pivot means extending through the jaws, the block and the bar and spring-means on the bar and pressing the bar and the lever-means in reverse directions.

5. The combination with a retort vessel, of a cover for the same said cover having a radial opening in its periphery, a bar pivotally attached to the vessel below said radial opening said bar being provided with a threaded upper end and having a longitudinal slot therein between the pivoted and threaded ends thereof, a block slidably

mounted on the bar, spring means on the threaded end of the bar beyond the block and seated against said block, an operating lever having a clamp-end to seat against the cover and a pivot pin extending through the lever, the block and passing through the slot in the bar.

6. The combination with a retort vessel, of a cover for the same said cover having a radial opening in its periphery, a bar pivotally attached to the vessel below said radial opening said bar being provided with a threaded upper end and having a longitudi-

nal slot therein between the pivoted and threaded ends thereof, a block slidably mounted on the bar, two springs of unequal strength on the threaded end of the bar, means for adjusting the springs to vary their pressure against the block, a clamping lever at the side of and pivoted with respect to the block and having a clamping face to seat against the cover and a roller device at one side of the block to also engage the cover. 15
20

In testimony whereof I affix my signature.

DANIEL W. DUDDERAR.
